UNITED STATES PATENT OFFICE.

BERNHARD ABELES, OF NEW YORK, N. Y., ASSIGNOR TO SCHEUER AND BROTHER, OF SAME PLACE.

DESIGN FOR A BELT-BODY.

SPECIFICATION forming part of Design No. 34,459, dated April 30, 1901.

Application filed March 22, 1901. Serial No. 52,437. Term of patent 7 years.

To all whom it may concern:

Be it known that I, BERNHARD ABELES, a citizen of the United States, residing at New York, borough of Manhattan, and State of New York, have invented and produced a new and original Design for Belt-Bodies, of which the following is a specification, reference being had to the accompanying drawings, in which—

Figure 1 is a plan view showing my design for belt-bodies, and Fig. 2 is a transverse section thereof.

The leading feature of my design is a series of longitudinal plait-like ribs or corrugations, which are ranged from side to side of the belt-body and which are formed with wide slanting or oblique faces, which terminate in rounded abrupt shoulders where one

rib joins the next, so that the ribs appear to incline or slant in the same direction.

A A indicate the longitudinal ribs, having slanting faces *a* and terminated where each ribs joins its neighbor with abrupt shoulders *a'*.

What I claim is—

The design for a belt-body, as shown and described.

In testimony that I claim the foregoing as my invention I have signed my name in presence of two subscribing witnesses.

BERNHARD ABELES.

Witnesses:

GEO. L. WHEELOCK,
GEO. C. GEIBEL.
